Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a bottom front perspective view of a shoe showing my new design;

FIG. 2 is a bottom view thereof;

FIG. 3 is a bottom rear perspective view thereof;

FIG. 4 is a bottom front perspective view of a shoe showing a second embodiment of my new design;

FIG. 5 is a bottom view thereof; and,

FIG. 6 is a bottom rear perspective view thereof.

The broken lines depicting the remainder of the shoe form no part of the claimed design.
